UNITED STATES PATENT OFFICE.

EDGAR M. BOUTON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed October 11, 1922. Serial No. 593,664.

To all whom it may concern:

Be it known that I, EDGAR M. BOUTON, a citizen of the United States, and a resident of East Pittsburgh, in the county of Allegheny and State of Pennsylvania, have invented a new and useful Improvement in Motor-Control Systems, of which the following is a specification.

My invention relates to motor-control systems, and it has particular relation to such systems of control as are employed in connection with elevators, hoists and similar machines.

One object of my invention is to control the starting and the stopping of a direct-current motor without employing the usual resistors in the armature circuit.

Another object of my invention is to provide automatic means for obtaining smooth and rapid acceleration and deceleration under all load conditions.

A further object of my invention is to obtain a fine degree of speed control and to obtain good regulation at low speeds.

Other objects of my invention will appear in the following detailed description.

Various systems of control have been previously devised to operate with greater efficiency than is possible with resistors connected in the armature circuit of a direct-current motor. Such systems provide some means for impressing a variable voltage upon the motor.

According to my invention, I propose to employ a motor-generator set of less capacity than is required in other systems of variable-voltage control and, in addition, I provide certain automatic features for improvement of the speed control of a hoisting motor.

My invention will be described in connection with the accompanying drawings, in which

Figure 1 is a diagrammatic representation of circuits and apparatus embodying my invention.

Figs. 2, 3, 4 and 5 represent schematically certain main connections employed in the operation of the system shown in Fig. 1.

Referring particularly to Fig. 1, a shunt wound direct-current motor 1, having an armature 2 and a field-magnet winding 3, is arranged for connection to a source of energy comprising conductors 4 and 5.

Switches 6, 7, 8 and 9 are employed for reversing the armature connections of the motor 1. A motor-generator set, comprising a pair of mechanically-connected armatures 11 and 12 and series field-magnet windings 13 and 14, may be connected in circuit with the motor 1 by means of switches 15 and 16. Shunt field-magnet windings 17 and 18 co-operate with the series windings 13 and 14, respectively. Shunt field rheostats 19 and 20 are mechanically connected to be operable simultaneously. A manually operable switch 22 is employed for controlling the electromagnetic switch 16.

Assuming the apparatus and switches in their illustrated and in-operative positions, either pair of reversing switches 6 and 8 or 7 and 9 may be operated by means of a master switch (not shown). Assuming also that line conductors 4 and 5 are receiving energy from the source of power, the motor-generator set will operate and its armatures 11 and 12 will supply a voltage opposed to that of the line voltage and of nearly equal value.

The power consumed by the motor-generator set is merely enough to supply the losses of the set when running idle. As illustrated, the field-magnet winding 18 is fully energized, and the winding 17 is supplied with a minimum energization. It will be apparent that the armature 12 delivers the major portion of the counter-voltage and, therefore, upon the closure of either pair of reversing switches, as 6 and 8, a minimum operating voltage, supplied by the armature 11, is impressed upon the motor armature 2. In addition to the current drawn from the armature 11, a portion of the current absorbed by the armature 2 is supplied from line conductors 4 and 5 through the armature 12 and the switch 16, which occupies its lower position.

The motor 1 is now assumed to operate at its minimum speed. It may be noted that, at low speeds of the armature 2, the shunt field-magnet winding 17 provides a minimum-voltage excitation for the armature 11 of the motor-generator set, while the series winding 13 has a larger corresponding effect upon the armature 11, since it carries the entire current generated by

the armature 11. This current is just sufficient to operate the armature 2 at its minimum speed, in accordance with the load conditions imposed upon the motor 1.

5 The current drawn from line conductors 4 and 5 by the armature 12 is sufficient to operate the armature 11 at substantially uniform speed, which is maintained on account of the maximum excitation of the 10 shunt field-magnet winding 18.

When it is desirable to accelerate the motor 1, switch 22 is closed and rheostats 19 and 20 are manipulated in a clockwise direction, thereby strengthening the field-magnet winding 17 and decreasing the strength of the field-magnet winding 18. With increased field strength, the armature 11 develops a corresponding increase in voltage, while the decrease in the strength of the 20 winding 18 effects a decrease in the voltage delivered by the armature 12. There is a corresponding increase in current through the armature 12 from line conductors 4 and 5. This increase is, of course, proportional 25 to the decrease in the counter-voltage delivered by the armature 12. The increase in current traversing the winding 14 tends to strengthen the "field" and offset the effect of too suddenly reducing the energization of 30 winding 18. When the field rheostats 19 and 20 are in the extreme right-hand positions, the motor 1 is smoothly and rapidly accelerated in accordance with the gradually decreasing voltage of the armature 12 and a 35 corresponding increase in voltage of the armature 11.

At a predetermined value of voltage of the armature 2, switch 15 is closed, since its operating coil 23 is responsive to the voltage 40 of the armature 2. The closure of switch 15 shunts the series field-magnet winding 14, and a portion of the current traversing the armature 12 now flows through the resistor 24 in shunt to the winding 14.

45 Switch 16 is provided with a hold-down coil 25, which is responsive to the voltage of the armature 12 and is arranged to release at a suitably low value of voltage when overcome by the opposing effect of the operating 50 coil 26, which is responsive to the voltage applied to the motor armature 2. Switch 16, in closing, connects the motor 1 directly to line conductors 4 and 5 and also connects the armature 11 of the motor-generator set 55 directly to the line. The armature 11 is now "motoring" and draws only sufficient current to overcome the losses of the motor-generator set which is now running idly with the armature 12 disconnected.

60 Fig. 2 represents the circuits for producing the minimum operating speed of the motor 1, and Fig. 3 represents the connections for an intermediate higher speed, with rheostats 19 and 20 in the extreme right-hand position and with switches 15 and 16

in the lower positions. Fig. 4 illustrates the transition period in which switch 15 is closed and series field-magnet winding 14 is shunted by resistor 24. In Fig. 5, the connections correspond to the maximum running speed of the motor 1, in which the motor is connected directly to the line.

To effect deceleration of the motor 1, switch 22 is opened and rheostats 19 and 20 are returned to their initial positions. 75 Switches 15 and 16 return to the lower positions to re-connect the armature 12 in circuit with armatures 2 and 11. Armature 12 generates a voltage that is opposed to the line voltage and will correspondingly reduce the voltage across the armature 2 of the motor 1. The motor 1 will now regenerate, returning current to the line until the counter-electromotive force generated by the armature 2 has been reduced to the voltage 80 impressed at its terminals. With the connections as illustrated in Fig. 2, the armature 12 absorbs its maximum voltage, and sufficient voltage is applied to the armature 2, as previously described for the starting 85 conditions, to operate the motor 1 at its minimum speed.

It should be noted that series field-magnet winding is chosen of suitable value, as previously indicated, to offset the effect of a 90 too sudden change in the field strength, caused by rapid manipulation of rheostat 20 in either direction. The proper selection of windings 14 and 18 eliminates the necessity of auxiliary control devices, such as fluttering relays, and greatly simplifies the control 100 and improves the operation of the system. It may also be noted that the armatures 11 and 12 of the motor-generator set are not required to continually carry the 105 full-load currents, and the set may, therefore, be economically designed and may be correspondingly reduced in size.

I am aware of the use of boosters in connection with the operation of series railway 110 motors, particularly as applied in regenerative systems. I believe that my system embodies novel features of control of particular value in connection with direct-current shunt-wound motors for hoisting applications. These features will be readily recognized by those skilled in the art, and modifications may be made without departing from 115 the spirit and scope of my invention.

120 I claim as my invention:

1. The combination with a motor and a source of energy therefor, of an auxiliary variable source of energy, means for simultaneously connecting the motor to both sources, means for varying the voltage impressed on said motor and means dependent upon the speed of said motor for rendering one of said sources ineffective.
2. The combination with an electric motor having an armature and a source of power 125

- therefor, of an auxiliary motor-generator set having its armatures connected electrically, means for connecting the armature of said motor in circuit with said motor-generator set, and means controlled in accordance with the speed of said motor for connecting said motor directly to the source of power.
3. The combination with an electric motor having an armature and a source of power therefor, of an auxiliary motor-generator set having its armatures connected electrically, means for connecting the armature of said motor in circuit with said motor-generator set, and means controlled in accordance with the speed of said motor for rendering said motor independent of said motor-generator set.
4. The combination with a motor and a source of energy therefor, of a motor-generator set comprising a pair of direct-current machines having compound field-magnet windings, means for connecting said motor in circuit with said machines, means for controlling the shunt field-magnet windings oppositely and means comprising the series field-magnet windings for modifying the effect of said shunt field-magnet windings.
5. The combination with a motor and a source of energy therefor, of a motor-generator set comprising a pair of direct-current machines having compound field-magnet windings, means for connecting said motor in circuit with said machines, means for controlling the shunt field-magnet windings oppositely, means comprising the series field-magnet windings for modifying the effect of said shunt field-magnet windings and means for shunting one of said series field-magnet windings.
6. The combination with a motor and a source of energy therefor, a motor-generator set comprising a pair of direct-current machines having compound field-magnet windings, means for connecting said motor in circuit with said machines, means for controlling the shunt field-magnet windings oppositely, means comprising the series field-magnet windings for modifying the effect of said shunt field-magnet windings, and means controlled in accordance with the motor speed for shunting one of said series field-magnet windings.
7. The combination with an electric motor having an armature and a source of power therefor, of an auxiliary motor-generator set having armatures connected in series relation with each other and to the source of power, means for connecting the armature of said motor in series relation with one of said auxiliary armatures and means controlled in accordance with the speed of said motor for connecting said motor directly to said source of power.
8. The combination with an electric motor having an armature and a source of power therefor, of an auxiliary motor-generator set having armatures connected in series relation with each other and to the source of power, means for connecting the armature of said motor in series relation with one of said auxiliary armatures and means controlled in accordance with the counter-electromotive force of said motor for connecting said motor directly to said source of power.
9. The combination with an electric motor having an armature and a source of power therefor, of an auxiliary motor-generator set having armatures connected in series relation with each other and to the source of power, means for connecting the armature of said motor in series relation with one of said auxiliary armatures and means controlled in accordance with the speed of said motor for disconnecting said motor from said motor-generator set.
10. The combination with an electric motor and a source of power therefor, of an auxiliary motor-generator set having its armatures connected in series relation, means for connecting said armatures to the source of power, means for connecting the motor in circuit with said armatures, means for varying the voltage of said armatures oppositely to control said motor and means dependent upon the relation of said voltages for accelerating said motor.

In testimony whereof, I have hereunto subscribed my name this 7th day of October 1922.

EDGAR M. BOUTON.
